(57) **CLAIM**

(21) Appl. No.: **29/306,920**

The ornamental design for an apparatus for supporting light-sensitive material, as shown and described.

(22) Filed: **Apr. 18, 2008**

DESCRIPTION

(51) **LOC (9) Cl.** **10-04**

FIG. 1 is a perspective view of a first embodiment of the apparatus for supporting light-sensitive material according to our design;

(52) **U.S. Cl.** **D10/81**

FIG. 2 is a partial, front elevational view of the embodiment illustrated in FIG. 1, the right, left, and rear elevational views being identical thereto; and,

(58) **Field of Classification Search** D10/81;

FIG. 3 is a top plan view of the embodiment illustrated in FIG. 1.

250/210, 226; 356/213-227, 432
